UNITED STATES PATENT OFFICE.

OSCAR KNOPE, OF FLINT, MICHIGAN.

AUTOMOBILE DOOR-LOCK.

1,173,441.

Specification of Letters Patent. Patented Feb. 29, 1916.

Application filed October 30, 1915. Serial No. 58,747.

To all whom it may concern:

Be it known that I, OSCAR KNOPE, a citizen of the United States of America, residing at Flint, in the county of Genesee and State of Michigan, have invented certain new and useful Improvements in Automobile Door-Locks, of which the following is a specification, reference being had therein to the accompanying drawings.

10 This invention relates to an automobile door lock, and more particularly to a novel latch by which an automobile door or any other door may be held in a closed position and at the same time compensate for expansion and contraction of latch elements or any inequalities between a door and door frame caused by vibrations or loose fitting.

15 The object of my invention is to provide a simple, durable and inexpensive latch of the above type possessing the above mentioned characteristics and others which make the latch particularly applicable to an automobile door. The latch mechanism is of such construction that the parts thereof 20 can be easily and quickly assembled and embodied in a door structure to be operated from the upper edge of the door or at any convenient place upon the same.

25 The mechanical construction entering into my improved latch will be hereinafter specifically described and then claimed, and reference will now be had to the drawing wherein—

30 Figure 1 is an elevation of the latch mechanism partly broken away; Fig. 2 is a plan of the same, partly broken away and partly in section, showing the mechanism in connection with a door frame and door; Fig. 3 is a perspective view of a detached latch member or bolt; Fig. 4 is a similar view of a detached strike plate and keeper, and Fig. 5 is a perspective view of a door frame plate illustrating a modification of my invention.

35 In the drawing, 1 denotes a door having a rabbeted edge 2 and said door at the rabbeted edge thereof is cut away as at 3, and 4, to provide clearance for a latch member or bolt 5 and an oblong casing 6. The oblong casing 6 forms part of a face plate 7 provided with openings 8 adapted to accommodate screws or other fastening means whereby it may be conveniently secured to the inner side of the door 1. The latch member or bolt 5 is slidable in the casing 6 and the upper and lower edges of said latch member have notches 9 and 10. The former

provides clearance for the lower end of a lever 11 fulcrumed upon a pivot pin 12 on the inner side of the face plate 7, and the door 1 is cut away to provide clearance for the upper end of said lever which is adapted to extend to the upper edge of the door whereby it may be moved to shift the latch member or bolt 5. The lower end or short arm of the lever 11 is held normally against an upstruck stop or lug 13 of the face plate 7 by a spring 14 on the inner side of the face plate 7, said spring restoring said lever to normal position after having been moved to shift the latch member or bolt 5.

40 Extending into the notch 10 of the latch member or bolt 5 is the end of a spiral or coiled spring 15 carried by the inner side of the face plate 7 below the casing 6, said spring holding the latch member or bolt 5 normally retracted. The outer end of the latch member or bolt 5 terminates in a U-shaped tapering hook 16 having a beveled bill 17. The hook end of said latch member or bolt can be easily moved in the cut away portion 3 of the door 1; a side plate 18 of the face plate 7 co-operating with the casing 6 in supporting the latch member or bolt 5 against vertical displacement.

45 The reference numeral 19 denotes a door frame provided with a strike plate 20 mounted in a rabbeted edge of said door frame. The strike plate 20 has a keeper 21 presenting a beveled or rounded surface 22 against which the bill 17 of the hook 16 rides 50 when the door is closed, the bill eventually receding into an opening 23 in the keeper to lock the door in a closed position. The construction of the keeper 21 is such as to provide a recess 24 in which the bill end 55 of the latch member or bolt may ride or vibrate without the bill riding out of the opening 23, consequently the door 1 cannot accidentally open due to any vibrations.

50 In Fig. 5 there is illustrated a portion of an automobile doorway as having a metallic plate 25 provided with a keeper 26, such plate and keeper being applicable to doors and doorways that are not rabbeted as shown in Fig. 2.

55 It is thought that the operation and utility of the door latch will be apparent without further description, and while in the drawings there are illustrated the preferred embodiments of my invention, it is to be understood that the structural elements are susceptible to such changes, in size,

100

110

shape and manner of assemblage, as fall within the scope of the appended claim.

What I claim is:—

A latch mechanism comprising a face plate adapted for attachment to a door, a casing carried by said face plate, a laterally disposed latch member shiftable in said casing, a pivoted lever carried by said face plate and loosely engaging in the upper edge of said latch member to facilitate shifting said latch member, a hook carried by said latch member and terminating in a beveled bill, a keeper adapted to receive the bill of

said hook and allow lateral movement of said hook without said bill becoming disengaged from said keeper, and means carried by said face plate and engaging in the lower edge thereof adapted to hold said latch member normally retracted.

In testimony whereof I affix my signature in presence of two witnesses.

OSCAR KNOPE.
